UNITED STATES PATENT OFFICE.

HERMAN G. JAKOBSSON, OF BETHLEHEM, PENNSYLVANIA.

COIN SORTING AND COUNTING MACHINE.

No. 875,712.

Specification of Letters Patent.

Patented Jan. 7, 1908.

Application filed November 13, 1906. Serial No. 343,223.

To all whom it may concern:

Be it known that I, HERMAN G. JAKOBSSON, a subject of the King of Sweden, residing at Bethlehem, in the county of Northampton and State of Pennsylvania, have invented certain new and useful Improvements in Coin Sorting and Counting Machines, of which the following is a specification.

My invention relates to sorting and counting devices especially adapted for sorting and counting coins, and consists of means whereby the different coins may be preliminarily separated so that the smaller coins will pass forward ahead of the larger ones, of means whereby there is a positive separation of the coins in proportion to their different sizes, and means whereby each series of coins is counted, as fully set forth hereinafter, and as illustrated in the accompanying drawing in

which Figure 1 illustrates in external elevation, an apparatus constructed in accordance with my improvements. Fig. 2 is an enlarged sectional view on the line 2—2, Fig. 1. Fig. 3 is a transverse sectional elevation. Fig. 4 is a section on the line 4—4, Fig. 3. Fig. 5 a plan of one of the distributers. Fig. 6 an elevation illustrating one of the counting mechanisms. Fig. 7 a longitudinal section showing the arrangement of parts where the sorting chute is straight instead of helical.

The construction of the apparatus shown in the different views is especially adapted for use in sorting coins of the denominations of 50, 25, and 10¢, United States money, but the same character of apparatus, only differently proportioned, is intended to be used where coins of different denominations are to be operated with.

The apparatus is contained within a suitable casing A, which may be of any desired contour and dimensions, and at the upper part of the apparatus is one or more distributers E, E', one above the other when more than one are employed, and each consisting of a smooth or corrugated conical disk, the apex of the cone being uppermost in the top distributer, while the next lower distributer is inverted, and preferably the second distributer E', forms the bottom of a casing C, supported by the body A, inclosing the upper distributer E, and supporting a central hopper D.

At different points of each distributer are arranged obstructions 1, in the form of rods, which as shown, extend vertically through

the distributer E to the distributer E', and these obstructions are so arranged that coins dumped into the hopper D and passing through the mouth x, thereof, onto the distributer E, make contact with these obstructions, and are temporarily arrested or deflected thereby.

Obviously the larger coins will more frequently contact with the obstructions than the smaller ones, so that the dimes will pass readily and quickly downwards towards the edge of the distributer, while quarters will be intercepted to a greater extent, and half dollars to a still greater extent, the result being that the small coins have a shorter course, while the others have a longer course, in proportion to their increased size, and thereby there is a preliminary sorting of the coins.

Preferably the distributer E has a series of radial peripheral fingers 2, separated by spaces, through which the coins will drop onto the lower distributer, and it has been found that the best results are secured by making the distributers so that their faces are at an angle of 70 degrees to the perpendicular, as thereby the coins will slide easily and surely, but not too rapidly.

As the face of the upper distributer is conical, the point of contact with any one coin will never be more than a diametrical line when the coin is not tilted to one side or the other, so that such a tilting is inevitable, and if one coin lies upon another, the inclination and the tilting of the coin below will result in at once causing the upper coin to slide off the lower one.

The above described separation of the coins is facilitated by arranging the fingers 2 at such distances apart that the larger coins will almost inevitably pass to the edge of the distributer, while the smaller ones will pass downward between the fingers. By this preliminary distribution of the coins, they will not be likely to become unduly intermingled in passing from the distributer portion of the apparatus to the main sorting part thereof.

As shown, the lower distributer or bottom of the casing C, has a central opening y, from which the coins drop into the upper end of a chute or trough F. As shown in Figs. 1 to 4, this chute or trough is helical, the coil extending to and supported by the body casing A, but in some apparatus it may be straight, as shown in Fig. 7, where it is a straight inclined trough or chute F'. The bottom 16,

of the chute is inclined to a horizontal, so that the coins sliding therein gravitate naturally towards the outer edge of the chute, and preferably the outer side of the chute 5 may be inclined inward at the top, so that if a coin should tend to roll upon its edge, it will not remain in an upright position, but will be caused to fall over and onto the bottom of the chute.

10 At different points, the bottom of the chute is slit upon lines 5, as best shown in Fig. 4, and the portion of the bottom within each line of slit is bent downwards, forming a downward inclined lip 6, the edge of the 15 depressed portion being carried sufficiently from the edge of the other portion to allow the passage from the chute of such coin as can pass onto the lip. The slits are formed in the bottom of the chute at different 20 distances from the outer side progressively further therefrom, so that the smaller coins only can pass onto the upper lip, the larger coins slipping over the depression until they meet a depression of sufficient width to permit them to lie upon the lip, and pass from the chute between the edges of the slit.

The coins which pass through the different slits or openings are received in the conductors G, which are preferably vertical, and the 30 channel in each of which the transverse section is but slightly larger than the transverse section of the coin to be received. As shown, each of these conductors flares or expands at the upper end so as to receive the 35 lip of the opening, through which the coin passes and each extends downward in position to conduct the coins to the base B, the drawer 20, which is proportionately subdivided so that the different coins will fall into 40 the different divisions or receptacles.

With the conductor is combined the counting mechanism which comprises a movable element or finger 21, and means whereby each movement of the said finger by the downward 45 passage of a coin is the means of imparting a movement of one step to a suitable counter or register.

While the finger and counter may be differently constructed, I prefer the construction 50 shown where the finger 21, is at the end of a pendent arm 22, swinging upon a shaft 23, which supports a ratchet wheel 24, suitably connected to actuate the indicator of the counting and registering mechanism. As 55 shown, the indicator is a hand 25, secured to the shaft, 23; and moving over a graduated disk 26.

With the pendent arm 22, is connected a weighted pall 27, which engages the teeth of 60 the ratchet wheel 24, and a detent pall 28, prevents any reverse motion of the wheel.

The nose of the finger 21, extends through an opening in the conductor G into the path 65 of the coins passing downward, so that the finger is swung outward in the direction of

the arrow, Fig. 6, as each coin passes in contact with the finger down the conductor, and as the arm 22 and finger swing back, the engagement of the pall 27, with the ratchet wheel turns the latter one step.

It will be evident that the counting and registering mechanism described may be used in connection with sorting mechanism different from that described, and also that the sorting mechanism may be used where the 75 counting mechanism is not required, or is of a different character.

Without limiting myself to the construction and arrangement of parts shown, I claim as my invention:

1. In a coin sorting device, the combination with a delivery hopper, of a fixed conical distributor arranged below the hopper, and a series of obstructions arranged to intercept the free passage of coins sliding radially on 85 the face of the distributor, the whole constructed to cause the coins to assume a flat-wise position upon the distributor.

2. In a coin sorting device, the combination of a delivery hopper, a plurality of fixed 90 conical distributors arranged one above the other and below the hopper, the adjacent distributors inverted in respect to each other, and a series of obstructions arranged to intercept the free passage of coins radially over 95 each distributor, the whole constructed to cause the coins to assume a flat-wise position upon the distributor.

3. The combination with the hopper of a coin sorter, of a sorter consisting of a conical 100 disk having peripheral radial arms and recesses, and a series of obstructions.

4. In a coin distributor, an inclined chute provided with a bottom transversely inclined, and with openings in said bottom of successively larger dimensions, and a blade below 105 each opening with an exit space between the edge of the opening and the face of the blade.

5. In a coin distributor, a chute having an inclined bottom provided with a succession 110 of openings each formed by slitting the bottom and bending the latter downward on the outer side of and from said slit, thus forming an inclined lip.

6. The combination, in a sorting machine, 115 with the sorting means and a conductor G having a lateral opening, of a ratchet wheel and shaft, an arm pendent from said shaft and carrying a weight, the end of which projects into the said conductor, and a pawl pivoted to the said arm to engage said ratchet wheel, and an indicator connected to be moved from the rotation of said wheel, for the purpose described.

In testimony whereof I affix my signature 120 in presence of two witnesses.

HERMAN G. JAKOBSSON.
